UNITED STATES PATENT OFFICE.

JOSEPH GEIGER, OF STEELTON, PENNSYLVANIA.

COKE-OVEN CONSTRUCTION.

Application filed September 11, 1922. Serial No. 587,469.

To all whom it may concern:

Be it known that I, JOSEPH GEIGER, a citizen of the United States, residing at Steelton, in the county of Dauphin and State 5 of Pennsylvania, have invented certain new and useful Improvements in Coke-Oven Constructions, of which the following is a specification.

This invention relates to improvements in 10 the construction of coke ovens and more especially coke ovens of the Semet-Solvay type.

One important feature of the invention resides in the construction of the sole floor 15 of the oven and in the form of the bricks which are employed in constructing this floor, one of the objects of the invention being to so form the bricks that when assembled they will provide a floor of substantial construction and not liable to disintegration.

It is another object of the present invention to so form the bricks comprising the sole floor as to effectually brace the bricks 25 which comprise the side walls of the passageway which runs beneath the said floor, and thus prevent collapse of the said side walls.

Another object of the invention is to provide a novel construction of sub-floor which 30 floor constitutes the bottom of the passageway above referred to, and so that the side walls of the passageway will be additionally braced against relative displacement both in an inward and outward direction.

Another object of the invention is to provide an improved construction and arrangement of bricks comprising the side walls of the oven chamber, the bricks being so formed and assembled as to effectually prevent collapse 35 of these walls or the inner and outer tiers comprising the same.

The invention generally has as its object to provide a minimum number of different kinds of bricks which may be assembled in 45 a definite order in building up the various walls and floors of a coke oven of the type heretofore mentioned, so that the completed oven will be substantial in construction and will not require frequent repairs to its walls and floors, and so that the cost of construction of such an oven may be materially

lowered by reason of the smaller number of bricks of different kinds required in its construction.

In the accompanying drawings: 55

Figure 1 is a vertical transverse sectional view through a coke oven constructed in accordance with the invention;

Figure 2 is a vertical longitudinal sectional view through the oven; 60

Figure 3 is a group perspective view illustrating a number of the bricks which are employed in building up the side walls of the oven chamber;

Figure 4 is a detail perspective view of one 65 of the bricks of the oven wall;

Figure 5 is a perspective view illustrating one of the members employed in the construction of the sole floor;

Figure 6 is a similar view of one of the 70 bricks employed in the construction of the sub-floor;

Figure 7 is a perspective view of one of 75 the flue bricks employed between the sole and sub-floors.

In the drawings, the numeral 1 indicates in general the oven chamber flanked by side walls 2 of any suitable construction and closed at the rear by a wall 3 and at the front by a wall 4. The sole floor of the oven 80 chamber is indicated in general by the numeral 5 and the sub-floor by the numeral 6, these floors, together with side walls indicated in general by the numeral 7, defining a passageway 8 extending longitudinally beneath the oven chamber, the walls 2 being extended to provide a foundation in which is provided a passageway 10 extending beneath the passageway 8. 85

Side walls indicated in general by the 90 numeral 11 are built within and beside the walls 2 and define the opposite sides of the oven chamber 1, and each of these side walls 11 comprises an inner tier of bricks indicated in general by the numeral 12 and an outer 95 tier indicated in general by the numeral 13, the tiers being spaced so as to provide combustion spaces 14 between the tiers and through which spaces the burning gases generated as a result of the coking operation, 100 may sweep, in the usual manner in ovens of this type.

The inner and outer tiers of bricks 12 and 13 are joined by bricks which are laid between them and one of which is indicated in general by the numeral 15 and the other by the numeral 16. Each of the bricks 15 is provided with a raised portion 17 extending from one end of the brick to a point adjacent the other end thereof and thus providing rabbets 18 at the longitudinal edges 10 of said brick and a transverse rabbet 19 at the last-mentioned end of the brick. The brick at its first-mentioned end is provided with a tongue 20 providing a rabbet 21 and it will be understood that a companion one 15 of the bricks 15 will be somewhat similarly formed so that when the bricks are fitted together, end for end, the tongue of one brick will seat in the rabbet 24 of the other brick. The bricks 15 are of solid or imperforate 20 construction, and therefore where they occur between the tiers 12 and 13, they define the closed tops and bottoms of passageways into which the space 14 is divided.

Communication is established between the 25 passageways referred to above, at suitable points, by the employment of bricks 16, and each of these bricks, which will hereinafter be referred to as flue bricks, is provided substantially centrally with a flue opening 22 and is formed upon its upper and under sides with ribs 23 and 24 which ribs extend at the opposite sides of the opening 22 and the opposing faces of which ribs constitute extensions of the side walls of this opening. 30 One end of the brick is indicated by the numeral 25, and the ends of the ribs 23 and 24 terminate, at this end of the brick, substantially in transverse alignment with the adjacent or corresponding end wall of the 35 flue opening 22, their said ends being free from connection with each other. At their other ends however the ribs 23 and 24 are connected by a portion 26 which is extended, as indicated by the numeral 27, to the extreme 40 corresponding end of the body of the brick. The formation of the ribs 23 and 24 provides rabbets 28 at the opposite longitudinal sides of the two faces of the brick and when the bricks 15 and 16 are arranged 45 one above another, the rabbets 18 and 28 will be correspondingly located, and the end portions 25 of the bricks 16 will be located opposite the rabbets 19 of the adjacent bricks 15. The tiers 12 and 13 50 are also connected or spanned by bricks which are indicated in general by the numeral 29 and each of which bricks has plane upper and lower ends adapted to seat snugly and firmly in the rabbet 19 against 55 the end portion 25 of the bricks 15 and 16 respectively. The bricks 29 are provided at their opposite sides with bosses 30 extending from their lower ends to a point spaced from their upper ends and of a 60 thickness equal to the thickness of the body

of the brick 29 and the upper end portion of each boss 30 has one of its faces disposed obliquely, as indicated by the numeral 31, so as to provide a substantially wedge-shaped shoulder 32.

The tiers 12 and 13 are constructed of 70 bricks indicated by the numerals 33, 34, 35 and 36. Each of the bricks 33 is provided at one vertical edge and adjacent its upper end with an overhanging nose 37 designed 75 to engage over the shoulder 32 of a companion one of the bricks 29, the lower end of the brick 33 resting in the rabbet 18 of the companion brick 15 and the upper end of the brick 33 supporting the corresponding 80 corner of the companion brick 16. It will be evident at this point that by the provision of the wedge-shaped bosses 30 and the overhanging noses 37, the bricks 29 and 33 are securely interlocked in building up the walls 85 11. In order that the bricks 33 may be braced with relation to the bricks 16, the said bricks 33 are formed in their upper edges or ends with rabbets 38 which receive 90 the unconnected end portions of the ribs 24 of the companion brick 16. The bricks 34, one of which is clearly shown in Figure 4 of the drawings, differ from the bricks 33 in the respect that these bricks 34 are provided with rabbets 39 in their lower ends 95 instead of being provided with the rabbets 38 in their upper ends as in the case of the said bricks 33 so as to adapt them to fit the ribs 23. A tongue 40 is formed longitudinally upon that edge of the brick 33 opposite 100 the edge at which the nose 37 is located, for a purpose to be presently explained, and similarly the corresponding edge of the brick 34 is formed with a tongue 41. Each brick 34 is provided with a nose 42 corresponding 105 to the nose 37 of the brick 33. Whereas in the case of the bricks 33, their rabbets 38 receive the unconnected ends of the ribs 23 and 24 upon the companion brick 16, the rabbets 39 of the bricks 34 likewise 110 receive these ribs of a companion brick 16, but in the first instance the bricks 33 support one of the bricks 16 and in the latter instance the bricks 34 are supported or disposed to rest upon one of the bricks 16. 115

The brick 35 is formed upon the vertical edge with a tongue 44 and in its opposite vertical edge with a groove 45, and one end of the brick may be plane or square wherever as the opposite end is rabbeted, as indicated 120 by the numeral 46. Thus, as illustrated in Figure 3 of the drawings, the plane end of one of the bricks 35 is adapted to be disposed to rest in the rabbet 18 of a companion brick 15 and with the tongue 40 of the companion brick 33 fitting in the groove 45, the tongue 44 of the brick 35 fitting in the groove 45 of a companion brick 35. The rabbets 46 of the bricks 35 are designed to 125 accommodate the ribs 23 or 24 of a com- 130

panion brick 16, and it will be understood that throughout the structure in general, the interfitting of the ribs and rabbets and tongues and grooves, serves to interlock or 5 relatively brace the several bricks and thus adds to the substantial construction of the walls of which they form a component part.

The sole floor 5 of the oven is made up of a number of bricks 47 each provided at its 10 opposite ends with oppositely disposed rabbets 48 so that when the bricks are disposed end to end, the rabbets will match in the manner illustrated in Figure 2, and a firm and gas-tight union will be provided between adjacent ones of the bricks. Each 15 brick 47 is formed upon its under side with a longitudinally extending boss 49 providing rabbets 50 which are designed to fit the upper end edges of the bricks comprising the side walls 7 of the passageway 8, the upper 20 portions of these side walls being in this manner relatively braced against inward collapse.

By reference to Figure 1 of the drawings, 25 this bracing of the side walls 7 will be evident, and it will also be observed by reference to the said figures that the opposite longitudinal edges of the bricks 47 abut against the lower portions of the opposing 30 faces of the lowermost course of bricks comprising the inner wall 12 so that the bricks of these courses at the opposite sides of the oven chamber are relatively braced against inward collapse.

35 The side walls 7 are built up of a number of bricks indicated in general by the numeral 51, two or more of the bricks 36, shown in Figure 7 of the drawings, being also employed at each side of the passageway 8 and at the rear end of the structure as illustrated in Figure 2 of the drawings. Each 40 of the bricks 36 is provided with an arched opening 52 and is formed in its opposite vertical edges with oppositely disposed rabbets 53, the brick in one face at its lower 45 end being rabbeted, as at 54, so as to provide tongues 55 at the opposite sides of the arched opening 52. The bricks 51 are provided at their opposite vertical edges with 50 rabbets 56 and at their lower ends are rabbeted as at 57 to provide tongues 58. In assembling the bricks 51 with one another and likewise in assembling the bricks 36 with one another and with the bricks 51, the 55 rabbeted vertical edges of the several bricks are interfitted and in this manner the walls 7 are built up. As before stated, the bosses 49 upon the under sides of the sole floor bricks 47 seat between the upper edges of the walls 7, the upper ends of the bricks 36 and 51 fitting in the rabbets 50 in the under sides of the said bricks 47.

The sub-floor 6 is built up of a suitable number of bricks indicated in general by 60 the numeral 59 and one of which is clearly

illustrated in Figure 6 of the drawings. As shown in this figure the brick 59 is provided at its opposite end edges with oppositely disposed rabbets 60 corresponding in purpose to the rabbets 48 of the bricks 47, and likewise each brick 59 is provided upon its under side with a boss 61 corresponding to the boss 49 of the brick 47 and designed to seat within the upper end of the passageway 19 in the foundation structure 9, as best illustrated in Figure 1, the bricks 59 being in this manner restrained against the lateral displacement and therefore maintained in proper alignment throughout the length of the sub-floor 6. Each brick 59 is further formed in its upper face near its lateral edges with parallel grooves 62, and these grooves receive the tongues 55 and 58 of the bricks 36 and 51 respectively, as shown in said Figure 1.

The walls 2 are provided with passageways 63 through which the products of combustion pass and may enter, through the arched openings 52 in the bricks 36, into the passageway 8 where they sweep longitudinally of the passageway and pass downwardly through the opening 64 left in the forward end of the sub-floor 6, and finally enter the passageway 10 and pass out through the stack or chimney 65 in the rear wall 3 of the oven.

Having thus described the invention, what is claimed as new is:

1. In coke oven wall construction, companion upright bricks, one having a substantially wedge-shaped, upwardly presented shoulder, and the other having a depending, overhanging nose engageable with said shoulder.

2. In coke oven construction, a wall comprising spaced inner and outer tiers of bricks laid in courses, and other bricks extending between the tiers, the last-mentioned bricks having substantially wedge-shaped, upwardly presented, lateral shoulders, and certain of the first-mentioned bricks having overhanging noses fitting over and interlocking with said shoulders.

3. In coke oven construction, a wall comprising spaced inner and outer tiers of bricks laid in courses, other bricks extending between the tiers, other bricks supported upon the second-mentioned bricks, the last-mentioned bricks have lateral shoulders provided with wedge-shaped upper ends, and certain of the first-mentioned bricks having noses fitting over and interlocking with the said shoulders.

4. In coke oven construction, a wall comprising spaced upright side bricks, a brick extending between the first-mentioned bricks and having shouldered engagement with the first-mentioned bricks, another brick extending between the first-mentioned bricks and having shouldered engagement

with the second-mentioned brick, and interlocking means upon the first and last-mentioned bricks.

5. In coke oven construction, an oven chamber having side walls, a floor extending between the side walls, a passageway extending beneath the floor and comprising side walls, and means constituting a part of the said floor extending between and relatively bracing the last-mentioned side walls.

6. In coke oven construction, an oven chamber comprising side walls, a passageway beneath the chamber also comprising side walls, and a floor for the chamber comprising a plurality of bricks disposed to rest at their edge portions upon the upper edges of the side walls of the passageway and extending between the side walls of the said chamber, the said bricks having shouldered under sides coating with the side walls of the passageway to relatively brace the said walls against inward displacement.

7. In coke oven construction, an oven chamber, a passageway extending beneath the chamber, the said chamber comprising side walls, the passageway comprising side walls each consisting of a number of bricks disposed in upright position, and a floor for the oven chamber comprising a plurality of bricks laid to rest upon the upper ends of the bricks of the side walls of the passageway and provided upon their under sides with rabbets fitting the upper ends of the said bricks of the passageway wall.

8. In coke oven construction, a foundation having a passageway extending therein, a floor disposed upon the foundation and comprising bricks arranged in a series and provided upon their under sides with shoulders coating with the opposite side walls of the passageway to prevent relative lateral displacement of the bricks, side walls upstanding from the floor, and an oven chamber including a sole floor extending between the upper portions of the last mentioned side walls, the said sole floor having shoulders engaging the said portions of the side walls to relatively brace the same against inward displacement.

9. In coke oven construction, a foundation having a passageway extending there-

in, a floor disposed upon the foundation and comprising bricks arranged in a series and provided upon their under sides with shoulders coating with the opposite side walls of the passageway to prevent relative lateral displacement of the bricks, side walls upstanding from the floor, and an oven chamber including a sole floor extending between the upper portions of the last mentioned side walls, the said sole floor having shoulders engaging the said portions of the said last mentioned side walls to relatively brace the same against inward displacement, the said chamber further including side walls relatively braced by the said sole floor against inward displacement.

10. In coke oven construction, an oven chamber, the said chamber including a sole floor, a foundation supporting the chamber, a passageway in the foundation, a sub-floor comprising a plurality of bricks laid in a series extending over the top of the last-mentioned passageway and having shoulders coating with the side walls of the passageway to prevent relative lateral displacement of the bricks, the said bricks having grooves in their upper faces, and spaced walls comprising series of bricks arranged upright upon the bricks of the said sub-floor and extending between said floor and the sole floor and having portions leading into the grooves in the bricks of the sub-floor.

11. In coke oven construction, a wall comprising upright side bricks, a brick extending between the first mentioned bricks and having shouldered engagement with the first-mentioned bricks and supporting the same, another brick extending between the ends of the first mentioned bricks and having shouldered engagement with the second mentioned brick, the first mentioned bricks having shoulders presented in an upward direction and beveled, and the third mentioned brick being provided at its opposite upright edges with overhanging noses having interlocking engagement over the said shoulders.

In testimony whereof I affix my signature.

JOSEPH GEIGER. [L. S.]
